(57) **CLAIM**

The ornamental design of a golf ball washer, as shown and described.

DESCRIPTION

FIG. 1 is an isometric view of a golf ball washer incorporating my new design, wherein the phantom lines form no part of the claimed design;

FIG. 2 is a front elevation view thereof;

FIG. 3 is a right side elevation view thereof, the left side elevation view being generally a mirror image;

FIG. 4 is a rear elevation view thereof;

FIG. 5 is a top plan view thereof; and,

FIG. 6 is a bottom plan view thereof.
